Patented Oct. 7, 1969

215,568

HOUSEHOLD BAG HEAT SEALING APPLIANCE

Thomas W. Kellogg, Newport Beach, Calif., assignor to
Dazey Products Company, Kansas City, Mo., a corpora-
tion of Missouri

Filed Sept. 13, 1968, Ser. No. 13,522

Term of patent 14 years

Int. Cl. D15—99

U.S. Cl. D55—1

FIGURE 1 is a perspective view of the household bag heat sealing appliance;

FIG. 2 is a top plan view of the appliance;

FIGS. 3 and 4 are elevational views of the appliance respectively taken from the opposite ends thereof;

FIG. 5 is an elevational view of the front of the appliance; and

FIG. 6 is an elevational view of the rear of the appliance.

The dominant features of my design reside in the portions shown in full lines.

I claim:

The ornamental design for a household bag heat sealing appliance, as shown and described.
